CLAIM

The ornamental design for an electric meter lock ring, as shown and described.

DESCRIPTION

FIG. 1 is a front elevational view of an electric meter lock ring showing my new design;

FIG. 2 is a right side elevational view thereof, the left side being a mirror image;

FIG. 3 is a rear elevational view thereof;

FIG. 4 is a bottom plan view thereof, the top being substantially similar in appearance; and

FIG. 5 is a partial sectional view taken in the direction of the line 5—5 of FIG. 3.

FIG. 3

FIG. 5

FIG. 2

FIG. 1

FIG. 4
